RANGE

John J. Toomey, Chicago, Ill.

Application September 26, 1931, Serial No. 565,363

1 Claim. (Cl. 126—37)

This invention relates particularly to gas ranges and electric ranges.

The primary object is to provide ranges of the type mentioned with a section preferably parallel with the cooking-top section which is adapted to the purpose of frying meats, preparing roasts, etc.

In accordance with the invention, the range is equipped substantially in the plane of the ordinary cooking-top equipment with facilities for frying large steaks, or the like, or for preparatory cooking roasts, which may afterwards be placed in the ordinary baking oven and browned, if desired.

In the accompanying drawings, the invention is shown applied to a flat-top range, but it is to be understood that, if desired, the cooking-top section and the frying section may be embodied in a range of the type in which an oven section extends above the level of the cooking-top and the frying-top sections.

In the drawings—

Figure 1 is a front elevational view of a range embodying the invention; Fig. 2, a plan view, slightly broken; Fig. 3, a sectional view, the section being taken parallel with the front of the range; Fig. 4, a broken sectional view, taken at right angles to the front side of the range; Fig. 5, a plan view of the burner, or heat-element, shown in Fig. 4; Fig. 6, a broken sectional view illustrating one form of cover for the frying-section of the range; Fig. 7, a broken sectional view corresponding with the section shown in Fig. 4, but showing the frying-pan equipped with a higher cover than is shown in Fig. 4, adapting the device to be used for cooking a roast; and Fig. 8, a broken vertical sectional view corresponding with Fig. 7, but showing a modification.

For convenience of description, the section of the range which can be used for frying large steaks or the like, and which can also be used for preparing a roast, is referred to as a "frying-section". It may be remarked at this point that this section is equipped with a relatively large burner, or heating element, which enables the section to be effectively employed for the purpose stated; also, roasting operations may be performed on this portion of the range in a highly convenient manner, and, if desired, the roast may finally be placed in the ordinary baking oven and the roasting operation completed in a few minutes to give a desirable browning effect to the roast.

Referring to Figs. 1-7, A designates the frame of the range, which may be constructed mainly,

or wholly, of sheet-metal; B and C broiler and baking ovens, respectively; D, a cooking-top section disposed above the oven C; and E, a supplemental section disposed parallel with and at substantially the same level as the cooking-top section, the section E being available for frying large steaks, preparing roasts, etc.

The range may be of any suitable construction. In the form shown it has a flat top, designated 1, which comprises a frame-member 1^a, grid sections 1^b, and a withdrawable, or removable, cover-plate 1^c.

The upper portion of the range is divided into a burner-chamber 2 within which are mounted the usual burners 2^a, shown as four in number; 15 and a burner-chamber 3 which extends from the front to the rear of the range and has mounted therein a large burner, or heating element, 3^a. The chambers 2 and 3 preferably are separated by a vertical partition 4. The bottom walls of 20 the burner-chambers are designated 5 and 6; the outer lateral walls of these chambers are designated 6^a; the rear wall is designated 6^b, and the front wall, or panel, is designated 6^c.

The frame-member 1^a at the top of the range 25 has the usual recesses forming a socket for the grids 1^b; and it has also an elongated, rectangular socket 1^d located in the upper portion of the burner-chamber 3. Within this socket is supported a removable hot-plate 7 which is in the 30 form of an elongated rectangular dished member, constituting a shallow pan. Thus, the member 7 has a flat bottom 7^a and marginal flanges 7^b which are supported on the depressed rim or socket-member 1^d.

The pan 7 is adapted to serve either as a frying-pan, in which case it may be equipped with a shallow or flat-cover 8 as shown in Fig. 4, or as a roasting pan, in which case it may be equipped with a deep, removable cover 9, as shown in 40 Fig. 7.

In the preferred arrangement, a gas manifold 10 extends along the front of the range just back of the panel 6^c, gas being supplied to the manifold through a pipe 10^a which may enter the burner-chamber through the rear wall of the range. The burners 2^a of the ordinary cooking-top portion of the stove are controlled by valves designated 11. The large burner of the supplemental cooking-top section E is controlled by a valve 50 designated 12.

In the upper portion of the broiler oven B is located a burner, or heating element, 13 which receives its gas supply from the manifold 10 through a pipe 13^a controlled by a valve 13^b.

The burner for the baking oven C is designated 14. It receives its gas supply from the manifold 10 through a pipe 14^a controlled by a valve 14^b.

5 The door of the broiler oven B is designated 15. It is equipped with a handle 15^a. The door of the baking oven C is designated 16. It is equipped with a handle 16^a. Storage drawers are provided in the base-portion of the range at 10 17 and 18, which may be utilized for any purpose desired.

15 The cover 1^c of the section E of the range may be made removable, or arranged to swing backwardly and upwardly in a manner now understood in the art. In the illustration given, the cover-plate is composed of two sections, one of which is connected by a hinge 19 to the rear portion of the top-frame 1^a, and the other of which is connected by a pivot 20 with the free edge of 20 the first-mentioned section. Thus, the cover may be swung upwardly and backwardly and folded upon itself. It may be supported in standing position in any suitable manner (not shown).

25 The top frame-member 1^a of the range has a depressed seat, indicated at 21, in which the cover-plate 1^c is supported.

30 The cover-plate 1^c, in the closed position, has its upper surface substantially flush with the upper surface of the top-frame 1^a and of the grids supported therein. Said cover-plate may rest in its seat, regardless of whether or not the frying-pan cover 8 is removed from the frying-pan.

35 Fig. 8 shows a modification of a supplemental cooking-top section, which is designated E'. The construction is similar to that already described, except that the removable frying-pan 7 and the cover-plate 1^c are dispensed with.

40 In their stead, a hot plate 7^c is employed as a cover for the burner-chamber 3. This plate has peripheral flanges 22 which embrace the upper portions of the vertical walls of the chamber 3. The body of the plate preferably is depressed slightly. In this form, the hot plate may be employed for frying purposes.

It is to be understood that the plate is substantially flush with the upper surface of the grids.

5 The improved construction provides a range having the ordinary cooking-top sections and in addition thereto a supplemental cooking-top section which is equipped with a relatively large heating element and which is covered by a large substantially rectangular hot plate, which may, if desired, be in the form of a removable pan. The cover-plate for the supplemental section, which 10 preferably is employed, is at a proper level to serve as a table, and cooking utensils may be shifted with ease from the grid-portion of the cooking-top to the supplemental section of the cooking-top.

15 Other advantages incidental to the improved range will be appreciated by those skilled in the art. While gas burners are shown as heating elements for the range, electric heating elements may be substituted, if desired.

20 The foregoing detailed description has been given for clearness of understanding only, and no unnecessary limitations should be understood therefrom, but the appended claims should be construed as broadly as permissible, in view of 25 the prior art.

What I regard as new, and desire to secure by Letters Patent, is:

20 A range comprising a main cooking-top section equipped with burners and a supplemental cooking-top section provided with a frame member having in one plane a socket, a hinged cover-plate mounted therein and substantially flush when closed with the cooking-top, said frame member being equipped in a lower plane with a second 30 socket in which is mounted a shallow pan-like hot plate provided with a removable imperforate cover having a substantially flat unobstructed upper surface, said second socket being of sufficient depth to permit the cover-plate to be closed with 35 said hot plate cover in position, and a burner disposed beneath said hot plate, extending the full length thereof.

JOHN J. TOOMEY.
